A. K. Spartell

ATTORNEY.

UNITED STATES PATENT OFFICE

WILLIAM C. BARBER, OF LOS ANGELES, CALIFORNIA

REINFORCING STIRRUP ASSEMBLY

Application filed August 31, 1927. Serial No. 216,578.

My invention relates to building specialties and more particularly to reenforcing devices for use in the construction of concrete building, bridges, etc. and the method of using said devices.

In connection with reinforced concrete construction more or less difficulty is experienced by builders in fixing the reenforcing metal within the forms so that it will not shift out of place when the concrete is being poured. Tying is usually resorted to, but this involves a considerable amount of extra labor and is not always effective.

The primary object of my invention is to provide reenforcing devices, especially adapted for use in the construction of reinforced concrete beams, girders and the like, which readily may be placed in the usual forms so that without being tied they will remain in properly spaced relation thereto when the concrete is being poured and while it is setting.

A further object is to provide means and a method whereby certain kinds of reinforced concrete construction jobs may be done satisfactorily with a considerable saving in time and labor over present methods.

Other objects and advantages will appear hereinafter and while I show herewith and will describe a preferred form of construction, I desire it to be understood that I do not limit myself to such preferred form but that various changes and adaptations may be made therein without departing from the spirit of my invention as hereinafter claimed.

Referring to the drawings which accompany this specification and form a part thereof.

Fig. 1 is a view in perspective of my re-enforcing stirrup assembly, designed for concrete beam construction.

Fig. 2 is a similar view of a chair device designed for use with the stirrup assembly shown in Fig. 1.

Fig. 3 is a side view of a tie device for holding in alignment the parts of a form such as is used in the construction of concrete beams, girders and walls.

Fig. 4 is a fragmentary view in perspective of a form for a concrete beam illustrating

the use of my stirrup assembly, chair and tie device.

The reenforcing stirrup assembly shown in Fig. 1 consists of a series of U-shaped pieces 10 of reenforcing rod-metal, the ends 55 of the upright parts 11 of which are bent to form anchor pins 12. These U-shaped pieces are arranged to extend transversely of the beam and are held rigidly in parallel spaced relation to each other by a straight 60 longitudinal tie-bar 13 which is electrically welded to the cross-bars 14 thereof, at their middle points and on their upper sides. Such stirrup assemblies are made in lengths 65 convenient for handling and placing in the forms.

The chair device shown in Fig. 2 is made of similar but somewhat lighter metal, relatively short pieces of which are bent at their middle points into leg-pieces 15 having the 70 form of an inverted letter V. Several such leg-pieces of equal size are held in suitably spaced and parallel relation to each other by a transverse tie-bar 17 which is electrically 75 welded to one side of each at a point somewhat below the bend or vertex 16 thereof. The length of the tie-bar corresponds approximately to the internal width of the form in which it is to be used and leg-pieces 80 15 are arranged in pairs, one pair being near each end as shown and others at intervals between them, in cases requiring more than two such pairs. The spaces 19 between the two pieces 15 of each pair is made to correspond to the thickness of the supplementary 85 reenforcing material to be used in the construction as will presently appear. The spacing from the ends of tie-bar 17 is such as to leave projecting ends 18 which serve to hold the chair device properly centered within the form and to bring spaces 19 just inside the uprights 11 of the stirrup assembly. The tie device shown in Fig. 3 is made preferably of heavy wire, a relatively long tie-piece 20, 90 somewhat longer than the external width of the form in which it is to be used, and two pairs of short pieces 21, electrically welded thereon at right angles thereto, one pair adjacent each end as shown. The individual 95

100

pieces 21, of each pair, are spaced apart a distance corresponding to the thickness of the lumber 22 used in the construction of the sides of the form.

5 The use of my stirrup assembly, chair device and tie device, is clearly illustrated in Fig. 4. The tie devices are placed at intervals between the upper and lower pieces and on the top piece of the side lumber 22 as 10 shown, and serve to prevent any spreading or bulging of the form, thus saving a considerable part of the labor and material usually employed in stiffening and bracing it. The form having been built up, chair devices, as shown in Fig. 2, are placed transversely at spaced intervals in the bottom thereof and suitable lengths of the stirrup assembly are placed thereon with longitudinal tie-bar 13 resting on transverse tie-bars 17. Finally the usual longitudinal reinforcing bars 23 are laid in the stirrup assembly 15 and in the spaces 19 of the chair devices so as to rest on cross-bars 14 of the stirrup assembly and on transverse tie-bars 17. It will 20 be seen that the chair devices so placed serve to support both the stirrup assembly and the longitudinal reinforcing bars in properly spaced relation to the bottom and sides of the form, no sidewise shifting being possible 25 because of the contact of projecting ends 18 of transverse tie-bars 17 with the sides of the form. Longitudinal bars 23 are held by the upper ends of the chair parts 15 and the stirrup assembly is held in turn by longitudinal bars 28. The form, thus equipped with reinforcing metal, is therefore in condition for the pouring of the concrete without further tying or fastening. The concrete having 30 been poured and allowed to set the removal of the side pieces 22 of the form may be accomplished by cutting off the projecting ends of tie-pieces 20 or by bending outside pieces 21 so as to permit the lumber to be pulled out from between them. The chair devices and tie devices are left imbedded in the completed structure to serve as additional reinforcement thereto.

While I have shown particular forms of stirrup assembly and chair device, by way of illustration, it should be understood that modified forms thereof may be made to suit different structural requirements without departing from the spirit of my invention as claimed.

55 I therefore claim as my invention:

The combination with reinforcing rods in concrete beam construction, of stirrup units made of a series of U-shaped rods held in parallel, spaced relation to each other by a tie-rod welded thereto and chair units made of inverted V-shaped legs held in parallel spaced relation to each other by tie-rods welded thereto, said V-shaped legs being spaced in pairs so that a reinforcing rod is held between each pair in spaced relation to

the bottom of the form while resting on the tie-rod to which said legs are welded and being spaced from the ends of said tie-rods so as to hold the reinforcing rods and through them said stirrup units in spaced relation to the sides of the form.

WILLIAM C. BARBER.
